US00D616831S

(12) **United States Design Patent**
Arenas et al.

(10) **Patent No.:** US D616,831 S
(45) **Date of Patent:** ** Jun. 1, 2010

(54) **MODULAR CONNECTOR**

(75) Inventors: **Alfredo Arenas**, Little Neck, NY (US);
Leslie Lindenstrauss, New York, NY (US); **Anthony Tufano**, North Massapequa, NY (US); **Dennis Oddsen**, Eaton's Neck, NY (US)

(73) Assignee: **Leviton Manufacturing Company, Inc.**, Melville, NY (US)

(**) Term: **14 Years**

(21) Appl. No.: **29/327,447**

(22) Filed: **Nov. 5, 2008**

CLAIM

The ornamental design for a modular connector, as shown and described.

DESCRIPTION

FIG. 1 shows a front perspective view of the module connector showing our design;

FIG. 2 shows a rear perspective view thereof;

FIG. 3 shows a rear view thereof;

FIG. 4 shows a front view thereof;

FIG. 5 shows a left-side view thereof;

FIG. 6 shows a right-side view thereof;

FIG. 7 shows a top-side view thereof; and,

FIG. 8 shows a bottom-side view thereof.

The broken line portion of the figure drawings is included to show unclaimed subject matter and forms no part of the claimed design.

1 Claim, 4 Drawing Sheets
